UNITED STATES PATENT OFFICE.

EDMUND C. BRITT, OF SEATTLE, WASHINGTON.

RAILWAY-CAR.

1,231,122.

Specification of Letters Patent. Patented June 26, 1917.

Application filed December 15, 1916. Serial No. 137,211.

To all whom it may concern:

Be it known that I, EDMUND C. BRITT, a citizen of the United States, residing at Seattle, in the county of King and State of Washington, have invented certain new and useful Improvements in Railway-Cars, of which the following is a specification.

This invention relates to railway freight cars, more especially to flat cars, and has for its primary object to provide such cars with means for supporting the stakes whereby logs transported on said cars may be maintained securely stacked thereon, and when such logs are to be unloaded, readily releasing said stakes which through the pressure of the logs will disengage them from the car and permit the logs to roll therefrom.

Another object of the invention is to provide stake supporting means for flat cars which securely hold said stakes in upright position against the pressure of the logs stacked against the inner sides thereof and which supporting means is in the form of a locking device that is operable from the opposite sides of the car, thus enabling the stakes to be removed from one side of the car without exposing the operators to danger of injury from the unloading logs.

A further object of the invention is to provide a flat car designed to transport logs with means for supporting said logs above the floor of the car and in connection with said means stake holding and locking devices which, while securely maintaining the stakes in their upright position, may, when desired, release said stakes to permit the car to be unloaded, the release being effected from the opposite side of the car and may be performed irrespective of the pressure against the stake produced by the logs carried on the car.

With the above as the principal objects in view, the invention consists of other novel constructions, combinations, and arrangements of parts hereinafter described, pointed out in the appended claims, and illustrated in the accompanying drawings, in which—

Figure 1 is an end view of a portion of a flat freight car with the improved log bunk and stake supporting means applied thereto, the central portion of the car being broken away.

Fig. 2 is a top plan view illustrating the improved log bunk and stake support as applied to a freight car,

Fig. 3 is an outside elevation of a portion

of the bunk and stake support, parts being shown in section on the line 3—3 of Fig. 2,

Fig. 4 is a transverse sectional view of the invention on the line 4—4 of Fig. 3, 60

Fig. 5 is a top plan view of a modified form of the log bunk and stake support,

Fig. 6 is a side view of the same,

Fig. 7 is a transverse sectional view on the line 7—7 of Fig. 6, and 65

Fig. 8 is an enlarged sectional view showing the stake locking device.

In the drawings, 10 indicates a freight car, a portion only of which is shown, the car being what is known as a flat car, 11 being the floor thereof which extends transversely across the car to the extreme sides thereof and on each side is generally bolted a bracket in which upright stakes are seated. In the present invention designed particularly to 75 be used on flat cars that transport timber, there is mounted on each side of the car and at each end or near each end thereof a metal bracket 12 made preferably of malleable iron or steel, each bracket including a flat 80 vertical plate 13, the lower half of which bears against the side of the car 10, while the upper half projects above the floor of the car. From the rear or inner side of each bracket there projects a horizontal plate 14 85

that rests upon the floor of the car and is secured thereto by bolts or other fastening means 15 passing through the plate 14 and into the wood work of the car. Ribs 16 are cast integral with the plates 13 and 14 from 90 the upper side of the plate 14 for the purpose of strengthening the bracket 12. Integral with each bracket 12 and projecting outwardly from the top thereof are two pockets 17, the pockets of each bracket being spaced 95 apart a certain distance and are each provided with a bottom 18 and a vertical outer end 19 to form seats for supporting the ends of transverse metal beams 20 to be herein-after more particularly described. Each 100

pocket 17 is braced and supported by a rib 21 that extends downwardly from said pocket and is integral therewith and with the vertical plate 13 of the bracket 12. Between the pockets of each bracket 12 and the 105 ribs 21 above the horizontal plate 14, the vertical plate is omitted in order to provide a passageway for the metal bars 20 and a timber 22 between said bars secured to the bars by through bolts 23. The brackets 12 110 are secured near the ends of a flat car on each side and opposite one another so that

the metal bars 20 which also extend transversely of the car may have their ends seated in the pockets 17 of the brackets. The ends of the timber however do not extend as far 5 as the bars 20 but terminate in contact with the inner faces of the vertical plates 13, as indicated in Fig. 4.

Near the bottom of each bracket 12 between the ribs 21 is a horizontal shelf or 10 support 24 with upwardly extending flanges 25 on the front and sides, the front flange having a central notch 26 as indicated in dotted lines in Fig. 3. Supported on each shelf 24 is the lower end of a stake 27 which 15 may be made from a section of rail, as shown in the drawing, or be formed of channel iron, T-bars, or I-beams, as desired. The stakes extend upwardly above the floor of the car to the required height and are maintained in their upright position by a disengageable locking device comprising a hook 28 secured to each stake and a longitudinally grooved roller 29 pivotally mounted in the ends of the bars 20. The hook 28 has 25 its engaging end 30 nearly as wide as the space between the beams 20, the opposite end of the hook being divided to form two ears 31 which extend around and on opposite sides of the stake and are secured 30 thereto by bolts or rivets 32. In the present instance where rails are used to form the stakes these fingers closely embrace the base of the rail and bear against the opposite sides of the web thereof as clearly shown in 35 Fig. 2. The engaging end 30 of the hook 28 is directed downwardly in position to engage a longitudinal groove 34 in the roller 29. This roller extends horizontally between the bars 20, from the ends of which roller 40 29 journals 35 project to rotate in circular openings 36 in the ends of the bars 20. One of said journals extends outwardly beyond the bar a short distance and is given a polygonal shape, as at 37, to receive one end of 45 a crank arm 38 by means of which the roller 29 is rocked. The opposite end of the arm 38 is pivotally connected to a horizontal rod 39 that extends transversely across the floor of the car and through a slot 40 in the plate 50 13 of the opposite bracket, the outer end of the rod 39 is turned upwardly as at 41 to provide a hand grip, by means of which the rod is actuated. A notch 42 is made in the under side of the rod near its outer end 55 to engage the plate 13 and lock the roller in position to hold the hook 30 from disengagement with the notch 34 in the roller 29. The outer ends of each timber 22 is cut away as at 43 to provide an opening for 60 the locking hook 28 and roller 29.

If desired, means for holding the notch 42 in the rod 39 in engagement with the plate 13 of bracket 12 may be provided and such means as shown consists of a swinging 65 latch 44 pivoted to the plate 13 above the

slot 40 and permitted to swing by gravity over the top of the bar 39 within the hand grip 41. When the rod 39 is to be operated, it is only necessary to swing the latch to one side beyond the rod so that the latter may be lifted.

As a modification of the log bunk I may dispense with the bracket 12, bars 20 and timber 22 and in place thereof provide two channel bars 45 held a suitable distance 75 apart by cross channel shaped brackets 46 and support said channel bars upon the floor of the car, their ends being provided with the circular openings 36 for rollers 29 similar to those in the preferred form of the 80 device. The ends of the channel bars 45 project a very short distance beyond the sides of the car and between them is placed a vertical plate 47 bolted to the car and having its bottom bent upon itself outwardly as at 48 to form a broad hook-like support having a central notch 49 and serving as a support for the bottom ends of the stake 27. The locking means comprising the roller 29 and the hook 28 will be the 90 same as in the preferred form of the device.

In loading a car equipped with the improved device, the ends of the logs are supported by the bunks at each end of the car 95 and are prevented from rolling sidewise from the car by the vertical stakes 27. These stakes, each of which has a hook 28 secured thereon, are supported at their lower ends by the shelves 24, the web of the stake 100 extending into the notch 26 of the shelf flange 25 and locks this end of the stake from being pushed laterally by the weight of the logs out of engagement with the support. The end 30 of the hook 28 engages with the 105 longitudinal slot 34 in the roller 29 and the latter being retained in the position shown in Fig. 4 by the locking engagement of the rod 39 with the plate 13 no lateral pressure of the load against the stakes will cause disengagement of these parts. An important feature in this connection is the relative position of the hook and roller with relation to the axis of rotation of the roller 29. As shown in Fig. 8, the bottom of the groove 110 34 against which the extremity 33 of the hook 28 engages is slightly above the axis of rotation of the roller and a little to the outside thereof. The lateral pressure on the stake therefore is applied to the roller 29 115 by the end 33 of the hook 28 a little above and beyond the center not sufficiently far in either direction to place a strain upon this connection, but sufficient to enable the roller to be easily operated when the rod 39 120 is disengaged from its connection with the plate 13 and drawn outwardly. The roller will thus be enabled to turn easily on its journals and disengage the hook from the 125 groove in the roller 29. When the roller has 130

been turned a distance sufficient to disengage the hook 28, the weight of the logs against the stakes 27 will be sufficient to push the stakes outwardly from the car and 5 being supported only by the shelf 24, the stakes will fall downward and permit the logs to roll off the bunk. It is desirable in this connection to secure the stakes each to the car by a chain of suitable length to 10 prevent the stakes being lost or left below the logs when the car is removed from the place of unloading.

What I claim is:

1. A locking device for railway car stakes 15 comprising a hook shaped member secured to the stake, a rocking roller journaled on the car and having a notch in its peripheral surface adapted to engage the extremity of the hook member and hold the stake in up- 20 right position, means operable from the opposite side of the car to rock said roller for engaging and disengaging the hook member, and means for locking said operable means to prevent movement of the roller when 25 the latter is engaged by the hook-shaped member.

2. A locking device for railway car stakes 30 comprising a hook shaped member secured to the stake, a rocking roller journaled on the car and having a notch in its peripheral surface to engage the extremity of the hook-shaped member and hold the stake in upright position, the engaging surface of 35 said parts contacting above the axis of the roller and tending to rock said roller and cause the disengagement of the hook therefrom when the stake is subjected to pressure from the inner side, an operating bar extending across the car to the opposite side 40 for rocking said roller to engage and disengage the hook member, and means for locking said bar to prevent movement of the roller when engaged by the hook-shaped member.

45 3. In a device of the class described, a car bunk, a stake adapted to be maintained in vertical position at each end of said bunk, and means for supporting said stake, said means comprising a shelf for the bottom of 50 the stake and a locking means between the stake and the bunk including a hook shaped

member and a grooved roller adapted to engage said member, and means for rocking the roller to disconnect the hook.

4. In a device of the class described, a 55 stake adapted to be supported in vertical position at the side of a car, a shelf carrying the lower end of said stake, a hook extending inwardly from said stake, a grooved rocking roller adapted to engage said hook and 60 maintain the stake in upright position, and means on the opposite side of the car for rocking the roller to disengage the hook.

5. In a device of the class described, a log 65 bunk comprising a timber and a metal bar bolted to each side of said timber and projecting at its ends beyond the end of the timber, a bracket on each side of the car having pockets to support the ends of said bars, a stake supported at its lower end by a 70 shelf on each of said brackets, a hook extending inwardly from said stake, a rocking roller journaled in said bunk bars and having a longitudinal groove to engage said hook, and means for rocking said roller to 75 disengage the hook.

6. In a device of the class described, a railroad car stake, a locking means for maintaining the same in vertical position against pressure on its inner side, said locking means 80 comprising an inwardly projecting hook with a downwardly projecting point, a roller having a longitudinal groove in one side thereof, the bearing surface of which groove to co-act with the point of the hook being 85 above and without the axis of rotation of the roller, and means on the opposite side of the car for turning said roller.

7. In a device of the class described, a log 90 bunk, a bracket on each side of a car to receive the ends of the bunk, said bracket comprising a vertical plate and a horizontal plate to bear on the outer side and the floor of a car, a pair of spaced pockets for the end of the bunk, and a shelf adapted to support the lower end of the stake.

In testimony whereof I affix my signature in presence of two witnesses.

EDMUND C. BRITT.
